[57] ABSTRACT

This monostable multivibrator includes a pair of NPN transistors arranged in the conventional manner with a capacitor connected to the collector electrode of the first transistor which conducts in the astable state, and with the capacitor and a first resistor connected to the base electrode of the second transistor which conducts in the stable state. The values of the first resistor and capacitor define the time constant that determines the time duration of operation in the astable state. The series combination of a second resistor and a third transistor which is a PNP type is connected in shunt with the first resistor, the base and collector electrodes of the third transistor being connected to the collector and base electrodes, respectively, of the second transistor. The third transistor facilitates rapid turn-on of the second transistor to terminate operation in the astable state and enables the resistance of the first resistor to be made larger than the conventional limiting value thereof that is determined by the base drive current in the second transistor and to thereby increase the time duration of the astable state.

MONOSTABLE MULTIVIBRATOR WITH A LONG TIME CONSTANT AND AN AUXILIARY TRANSISTOR FOR ENSURING TURN-ON OF THE TRANSISTOR CONDUCTING IN THE STABLE STATE

BACKGROUND OF INVENTION

This invention relates to multivibrators and more particularly to an improved monostable multivibrator that operates for a long time interval in the astable state.

In various timing applications a long and accurate time delay is required. It is also desirable that devices producing this time delay be reproducible without having to select and match components thereof. The prior art monostable multivibrator illustrated in FIG. 1 is one device that is employed to produce a time delay which here may be defined as the time duration of conduction in the astable state thereof. In the stable or rest state, transistor Q_1 is cut off and transistor Q_2 is saturated. In response to a timing pulse on line 10 to the collector of Q_1 and base of Q_2 , this multivibrator operates in the switched or astable state with Q_1 conducting and Q_2 cut off for the time interval determined by the time constant set by resistor 11 and capacitor 12. The maximum value of resistor 11 in this prior art multivibrator for rapid turn-on of Q_2 is determined by the base drive current thereof required for switching conduction states of these transistors. The capacitance of capacitor 12 must therefore be increased to increase the time delay of this circuit above a limiting value set by resistor 11. Stable, low tolerance capacitors having large values of capacitance, which are required to reproducibly obtain an accurate time delay, are physically large and expensive. Tantalum capacitors, for example, which have large values of capacitance and are physically small, are high tolerance devices and therefore not suitable for use in such applications.

An object of this invention is the provision of an improved monostable multivibrator overcoming these disadvantages.

SUMMARY OF INVENTION

In accordance with this invention, a third complementary transistor is connected in the base-collector circuit of the transistor that is cut off in the astable state of a dual transistor monostable multivibrator to assure rapid turn-on of the latter transistor as the resistance in series with the base electrode thereof, which determines the duration of operation in the astable state, is increased.

BRIEF DESCRIPTION OF DRAWING

This invention will be more fully understood from the following detailed description thereof, taken in conjunction with the attached drawing in which:

FIG. 1 is a schematic circuit diagram of a prior art multivibrator which was referred to in the discussion of the background of the invention; and

FIG. 2 is a schematic circuit diagram of a monostable multivibrator embodying this invention.

DESCRIPTION OF PREFERRED EMBODIMENTS

Referring now to the embodiment of this invention illustrated in FIG. 2, similar components as are employed in the conventional monostable multivibrator in

FIG. 1 are designated by the same reference characters. The conventional monostable multivibrator comprises transistors Q_1 and Q_2 having associated collector resistors 14 and 15, Q_1 base resistor 16, input diode gates 17, and the resistor 11 and capacitor 12.

In accordance with this invention, a long time constant that determines the duration of operation in the astable state is obtained by using a resistor 11 having a resistance that is greater than the conventional limiting value thereof without increasing the capacitance of capacitor 12. This is made possible by employing a switching element in the base circuit of Q_2 to switch a small resistance into this base circuit to facilitate turn-on of Q_2 and to switch a large resistance into this base circuit when Q_2 is cut off and capacitor 12 is discharging. In a preferred embodiment of this invention, the switching element is a PNP transistor Q_3 having its collector and base electrodes connected to the base and collector electrodes, respectively, of Q_2 . Q_3 may, by way of example, be a 2N2907 transistor. Q_1 and Q_2 are NPN types which may, for example, be 2N2222 transistors. Alternatively, Q_1 and Q_2 may be PNP transistors and Q_3 may be an NPN transistor.

A voltage divider comprising resistors 21 and 22 is connected between the supply potential $+V_s$ and ground with the emitter electrode of Q_3 connected to the junction 23. The values of resistors 21 and 22 are selected to bias the emitter electrode of Q_3 to insure that when Q_2 is cut off the emitter of Q_3 is at a low enough potential to insure that the Q_2 collector potential during cutoff keeps Q_3 turned off. Q_3 will saturate when the base voltage thereof is reduced to the base-emitter turn-on potential which occurs when a very small collector current is drawn by Q_2 . The value of resistor 21 is much less than that of resistor 11. The diodes 24 and 25 provide a constant 0.7 volt drop in the base and collector circuits of Q_1 and Q_2 , respectively, when these transistors are conducting. These constant voltage drops insure that the base of Q_1 and the collector of Q_2 are maintained at different potentials so they do not oscillate on and off. The output of the multivibrator is coupled on line 27 from the collector of Q_2 , for example.

In the quiescent or rest state of the multivibrator, Q_2 and Q_3 are saturated and Q_1 is cut off. During this time interval, capacitor 12 charges through resistor 14 and the base-emitter junction of Q_2 to impress a voltage that is approximately equal to the supply potential V_s across the capacitor. This takes approximately four time constants of resistor 11 and capacitor 12. When a negative trigger pulse is applied on input line 10 to the collector of Q_1 , this transistor starts to conduct. At this instant, the voltage across capacitor 12 appears as a large negative voltage applied to the collector of Q_3 and base of Q_2 which abruptly decreases the rates of conduction thereof. The resultant voltage change in the Q_2 collector voltage across resistor 15 turns Q_1 on harder and regenerative switching action rapidly causes Q_1 to be saturated and Q_2 and Q_3 to be cut off.

In this astable state, Q_3 essentially presents an open circuit in shunt with resistor 11. Thus, capacitor 12 discharges from the potential of approximately $-V_s$, that is impressed on it toward the supply potential $+V_s$, through Q_1 and resistor 11 at a rate determined by the time constant of this resistor and the capacitor. When the charge voltage on capacitor 12 exceeds the ground reference potential by the base-emitter voltage drop of

Q_2 this transistor draws very small base and collector currents, the former current being much less than that required to turn Q_2 on hard and the latter being much less than that required to drive Q_1 into cutoff. When the drop in collector voltage on Q_2 exceeds the base-emitter voltage drop of Q_3 , the latter transistor immediately saturates and injects a large base drive current through the base-emitter junction of Q_2 . This base current on line 26 drives Q_2 into saturation. Thus, Q_3 essentially amplifies the base current of Q_2 to provide an excess of base drive for Q_2 and produces sharp turn-on of the latter. Through regenerative switching action, Q_1 is rapidly driven into cutoff. In this manner, Q_3 enables Q_2 to turn on rapidly even when the value of resistor 11 is large, i.e., much larger than the conventional limiting value thereof for providing sufficient base drive to turn Q_2 on. The multivibrator continues to operate in this stable state until another trigger pulse is received on input line 10.

In an embodiment of this invention which was built and tested, Q_1 and Q_2 were 2N2222 transistors and Q_3 was a 2N2907 transistor. The limiting value of resistor 11 for turn-on of Q_2 in FIG. 1 is 86 kilohms. The resistance of resistor 11 is computed as follows. Assuming that the supply voltage $V_s = 5$ volts, and Q_2 has a $\beta_{min} = 20$ and collector current $I_c = 1$ mA, then the base current to saturate Q_2 is

$$I_B = I_c / \beta_{min} = 0.05 \text{ mA.}$$

The maximum resistance of resistor 11 is then

$$R_{11} = V_s - V_{BE}(\text{on}) / I_B = 86 \text{ kilohms.}$$

In the circuit of FIG. 2, when resistor 11 had a resistance that was five times this conventional limiting value thereof, Q_2 still exhibited rapid and repeatable turn-on. The limiting value of resistor 11 in FIG. 2 is governed by the collector-base leakage currents in Q_2 and Q_3 which must remain small with respect to the capacitor discharge current. In this circuit in which a long time delay of 80 ms was obtained, the capacitance of capacitor 12 was maintained at less than 0.5 μF .

Although this invention is described in relation to a specific embodiment thereof, changes, modifications and improvements thereof will be obvious to those skilled in the art. By way of example, transistors Q_2 and Q_3 may be replaced with a silicon controlled rectifier (SCR) or PNPN transistor in which a terminal post is brought out from the second control or gate electrode thereof.

What is claimed is:

1. A monostable multivibrator comprising a first transistor of one type having emitter, base and collector electrodes and being nonconductive in the stable state of the multivibrator; a second transistor of the same type having emitter, base and collector electrodes and being conductive in the stable state of the multivibrator; said first and second transistor emitter electrodes being directly electrically connected to a ground reference potential; a power supply; first means coupling said first and second transistor collector electrodes to said power supply; second means coupling said second transistor collector electrode to said first transistor base electrode; a first timing resistor connected between said second transistor base electrode and said power supply; a timing capacitor connected between said first transistor collector electrode and said second transistor base electrode; said capacitor charging through said second transistor during conduction thereof and discharging through said first transistor during conduction of said first transistor; third means coupling an input signal to one of said first and second transistors for causing the multivibrator to operate in the astable state; and transistor switching operating in a first state and responsive to current drawn by said second transistor in returning to operation in the stable state for operating said transistor switching means in a second state for rapidly driving said second transistor into saturation when the latter draws a base drive current that is less than the conventional turn-on current thereof.

a timing capacitor connected between said first transistor collector electrode and said second transistor base electrode; said capacitor charging through said second transistor during conduction thereof and discharging through said first transistor during conduction of said first transistor;

third means coupling an input signal to one of said first and second transistors for causing the multivibrator to operate in the astable state; and transistor switching operating in a first state and responsive to current drawn by said second transistor in returning to operation in the stable state for operating said transistor switching means in a second state for rapidly driving said second transistor into saturation when the latter draws a base drive current that is less than the conventional turn-on current thereof.

2. A monostable multivibrator comprising a first transistor of one type having emitter, base and collector electrodes and being nonconductive in the stable state of the multivibrator; a second transistor of the same type having emitter, base and collector electrodes and being conductive in the stable state of the multivibrator; said first and second transistor emitter electrodes being directly electrically connected to a ground reference potential;

a power supply;

first means coupling said first and second transistor collector electrodes to said power supply;

second means coupling said second transistor collector electrode to said first transistor base electrode; a first timing resistor connected between said second transistor base electrode and said power supply; a timing capacitor connected between said first transistor collector electrode and said second transistor base electrode; said capacitor charging through said second transistor during conduction thereof and discharging through said first transistor during conduction of said first transistor;

third means coupling an input signal to one of said first and second transistors for causing the multivibrator to operate in the astable state; and

switching means responsive to current drawn by said second transistor in returning to operation in the stable state for rapidly driving said second transistor into saturation when the latter draws a base drive current that is less than the conventional turn-on current thereof;

said switching means comprising a second resistor, and a third transistor having conduction characteristics opposite to those of said other transistors, having a collector electrode DC coupled to the second transistor base electrode, having a base electrode DC coupled to the second transistor collector electrode, and having an emitter electrode connected through said second resistor to said power supply, said third transistor conducting throughout conduction of said second transistor.

3. The multivibrator according to claim 2 wherein the resistance of said second resistor is less than that of said first resistor and the resistance of said first resistor is greater than the conventional limiting value thereof.

4. The multivibrator according to claim 3 including a third resistor connected in series with said second re-

sistor across said power supply and forming a voltage divider for biasing said third transistor.

5. The multivibrator according to claim 4 wherein said second coupling means comprises a first diode connected in series between the second transistor col-

lector electrode and said power supply and a second diode connected between the first transistor base electrode and the side of said first diode which is spaced away from said second transistor collector electrode.
